TEMPLE ROLL

Charles Thomas Dickey, Elizabeth, N. J., assignor
to Rodic Rubber Corporation, Garwood, N. J.,
a corporation of Delaware

Application March 25, 1939, Serial No. 264,065

4 Claims. (Cl. 139—296)

This invention relates to a roll for use in a loom temple.

As is well known to those skilled in the art, a loom temple is employed at each side of the loom adjacent the fell of the cloth being woven for the purpose of uniformly maintaining the cloth stretched widthwise.

In connection with various type of fabrics, for example, as those composed wholly or largely of rayon or cellulose ester filaments as acetated cellulose, or those of a fine and delicate nature, it has long been customary to have the surface of the roll which engages the cloth composed of rubber or rubber composition.

15 The ideal temple roll according to my experiments, is approached wherein a permanent thermoplastic, neutral compound is used as the temple roll, and has imbedded therein a multiplicity of outwardly-projecting fixed fiber ends to which the frictional-gripping capacity is primarily due, that is, wherein the friction results primarily from a number of frayed fiber ends immovably imbedded, contacting the delicate filaments constituting the goods being processed.

20 This invention is a continuation in part of my copending application Serial No. 249,207, filed January 4, 1939 for "Temple roll and process of manufacture".

One of the objects of the present invention is 25 to provide a construction of that type of temple roll employing a non-rubber body, in which the above indicated and other disadvantages are substantially non-existent, as will be herein more particularly pointed out.

Another object is to provide a temple roll having the initial desired frictional gripping surface, which remains uniform and substantially unimpaired for an indefinite period of time.

30 A third object is to provide a temple roll of required frictional gripping surface which is unacted upon and unimpaired by any of the components of, in, or evolved incident to the textile being woven.

A further object is to provide a temple roll 35 wherein the surface passing in contact with the cloth, does not leave a mark or streak, or deposit material on the goods, as is the case where a rubber-faced roll is used, especially when the rubber has been softened by the "fumes" from the filaments being woven. This is an important point because the goods are plain woven white and afterwards dyed. Even if an almost unnoticeable streak is left on the goods from deposition of tiny traces of rubber, this materially interferes with uniform penetration of dyestuff in the dyeing

operation for the reason that rubber is absolutely insoluble in water, and the result is that uneven and unlevel dyeings result.

Other objects of the invention will appear more fully and clearly from the accompanying description and drawing, and will be particularly pointed out in the claims.

The general nature, function and purpose of a loom temple of the roll type are so well known and familiar to those skilled in the art, that it here only becomes necessary to illustrate a portion of one typical form of a temple, together with preferred forms of the invention embodied therein.

In the drawing and illustrative examples are shown and described several preferred forms of temple roll embodying my invention.

Fig. 1 is an end elevation of a temple head with the form of roll embodying the invention located therein;

Fig. 2 is a top plan view of the construction shown in Fig. 1;

Fig. 3 is a face view of one of the units from which the roll is fabricated;

Fig. 4 is a side view of the unit shown in Fig. 3;

Fig. 5 is a longitudinal cross section through a fabricated roll in an intermediate stage of manufacture;

Fig. 6 is a longitudinal cross section through a finished roll.

The invention is shown in connection with the usual type of temple wherein two rolls are rotatively mounted. The temples are arranged in pairs, one at each side of the loom, and may be termed right-handed and left-handed since their function is to laterally stretch the cloth being woven to the right and left side of the loom. The construction of the temple roll is the same in both cases and therefore only a right-handed temple roll has been illustrated.

The form of roll embodied in the present invention is adapted for use in substantially all types of roll temples.

The temple illustrated in Figures 1 and 2 comprises an arm 1, of which only a portion is shown and by which it is mounted upon the loom at the forward end, and a main body portion or pod 2 formed thereon having a trough-like shape in which the rolls are mounted. The temple rolls are journaled on pins 3 supported in the end walls of the pod 2, the inner ends 4 being fitted into the end wall 5 and the outer ends being provided with enlarged screw-threaded heads 6 which are tightly threaded into the end wall 1.

The temple roll 8, to perform its function of putting lateral tension on the cloth being woven, has its surface formed into alternating ridges 9 and grooves 10 arranged in the form of a helix. 5 The outer part of the roll 8 in which the ridges 9 and grooves 10 are later formed is fabricated or built up of a plurality of washer-shaped members 14 in which the outside diameter is slightly greater than that of the finished roll and the 10 diameter of the hole 15 is slightly larger than pins 3. A suitable rod or mandrel of steel or other suitable material is shown at 16 of Fig. 5.

To construct the roll 8, the proper number of 15 impregnated washer-like members 14 are closely placed on the rod 16 in sufficient number so that when compacted together, a temple roll of the desired length will be formed. The rod with its 20 assembled washers 14 thereon, is then subjected to pressure and heat, in a device having dies with an internal configuration which will compress, 25 distort, groove and furrow the substantially cylindrical shape of the series of members 14 into the helically arranged ridges 9 and grooves 10 of the finished roll 8. During this operation the 30 members 14 are so compressed and merged into one another that they form a highly resistant, substantially one piece unit having the characteristics desirable in a temple roll.

After the compression operation, the rod, which 35 has been used to align the washer-like members, is removed, leaving the temple roll as shown in Fig. 6. If desired, the temple roll may be molded with one or both ends of small outer diameter than the rest of the temple roll. In the drawing, Fig. 6, illustrates such a roll with one end of smaller outside diameter.

The members 14 are preferably of woven natural or artificial fibers or admixtures thereof as cotton, linen, wool, silk or rayon, and impregnated 40 with a thermoplastic body or bodies which are substantially unaffected by the fibers being woven, or materials contained therein or evolved therefrom. And conversely, solvents, non-solvents, diluents, softeners and plasticizing bodies 45 used in conjunction with the impregnating material must be substantially devoid of solvent action upon the filaments constituting the textile being treated.

Suitable impregnating bodies for this purpose 50 are cellulose derivatives in the thermoplasticized condition as cellulose esters and ethers, or a thermoplastic natural or synthetic resinous body or mixtures thereof, or a thermoplastic mixture of cellulose derivative and resinous body in proportions varying with the chemical composition and physical constants of the same.

In carrying the above method of my invention into effect, I may take 4 pounds avoirdupois of 55 ten ounce duck, drill or canvas, and permeate or 60 impregnate the same with a resinous body of the vinol type rendered fluid by solution in a volatile petroleum hydrocarbon mixture or other solvent or solvent combination, preferably of such flowability as will thoroughly permeate the woven 65 fibers with the minimum of solvent, excess of the latter after impregnation, being removed as by an evaporative step.

The canvas, after removal of volatile portion 70 therefrom, weighs about 6 pounds 11 ounces 75 avoirdupois. From this impregnated textile, washer-like members are cut as shown in Fig. 4.

Or the original textile may be cut into washer-like members which afterwards are impregnated in manner as above indicated or its substantial 75 equivalent.

In an alternative method, the woven fiber may be impregnated as in the previous example, using a cellulose derivative as an etherized cellulose, preferably of relatively high degree of etherification as, for example, highly ethylated ethylcellulose or highly benzylated benzylcellulose, or mixtures of the same, with suitable solvents and thermoplasticizing bodies if desired. 5

A plurality of such impregnated textile sheets are then stacked one upon the other, in a number so that when pressed together into a unitary-appearing body, a slab of thickness equivalent to the desired length of the finished temple roll is formed. 10

The plurality of sheets are then compacted in 15 any suitable manner.

The impregnated sheets after being compacted into a unitary block or slab of thickness approximating the length of the plurality of washer-like members 14 shown in Fig. 5 are then cut in a 20 direction perpendicular to the long axis of the threads, so as to form unitary hollow cylindrical bodies with inner diameter nearly equal to the outer diameter of pin 3 and of outer diameter substantially the same as 14, and in appearance 25 will be the equivalent of 14 in Figure 5, except that the plurality of 14 shown mounted on 16, is replaced by a unitary member.

Compression is then applied as described in the 30 previous example, to produce the equivalent of the finished temple roll shown in Figure 7.

In the foregoing examples, after removal from the press, the helically arranged ridges 9 are more or less rounded from thermoplastic thereon. The 35 final operation is a grinding or abrasive treatment whereby 9 is smoothed until a flattened face is formed, as shown at 9 in Figure 6.

The plurality of woven or unwoven threads may be dyed, mercerized or otherwise treated before 40 impregnation, and the impregnating medium may be colored as by addition of dyestuff or pigment.

The important feature of this invention resides in, and its efficiency depends upon, the relative percentage of raw edges of outwardly-projecting fibers constituting as the fabric-engaging surface 45 the periphery of 14 of Figure 5, compacted and held together by a thermoplastic body not deleteriously effected by components in, or evolved from, the fibers or filaments passing over the same, constituting the helically raised ridges 50 9 of Figure 6, wherein the surface of 9 is substantially parallel with the inner cylindrical hole 15.

I claim:

1. A temple roll of a unitary body composed of a helically grooved cylinder comprising a plurality of compacted layers of woven fiber with outwardly-projecting ends embedded in a thermoplastic synthetic resin of the polyvinyl type said temple roll being adapted to engage a cloth surface without damaging the same, and retain a satisfactory 60 uniform cloth-engaging, frictional-gripping surface during the wearing of said surface.

2. A temple roll of a unitary body composed of a spirally channelled cylinder comprising a plurality of compacted layers of woven fibers with 65 outwardly-projecting raw ends bonded together by a thermoplastic synthetic resin substantially inert to acids or alkalis said temple roll being adapted to engage a cloth surface without damaging the same and retain a permanent cloth- 70 engaging and frictionally-gripping surface during wear.

3. A temple roll of a unitary body composed of a helically grooved cylinder comprising a plurality of compacted layers of woven fibers with out- 75

wardly projecting ends embedded in an etherized cellulose said cylinder being adapted to engage a cloth surface without damaging the same and retain a satisfactory uniform cloth-engaging and frictionally-gripping surface during the wearing of said surface.

4. A temple roll of a unitary body composed of a helically grooved cylinder comprising a plurality of compacted layers of woven fibers with

outwardly-projecting raw ends bonded together by a thermoplastic synthetic resin of the polyvinyl type said cylinder being adapted to engage a cloth surface without damaging the same and retain a satisfactory uniform cloth-engaging and frictionally-gripping surface during the wearing of said surface.

CHARLES THOMAS DICKEY.
